UNITED STATES PATENT OFFICE.

DANIEL B. LUTEN, OF INDIANAPOLIS, INDIANA.

BRIDGE OR ARCH OF CONCRETE OR OTHER ANALOGOUS MATERIALS.

No. 923,058.

Specification of Letters Patent. Patented May 25, 1909.

Application filed April 1, 1907. Serial No. 365,846.

To all whom it may concern:

Be it known that I, DANIEL B. LUTEN, a citizen of the United States, residing at Indianapolis, in the county of Marion and State 5 of Indiana, have invented new and useful Improvements in Bridges or Arches of Concrete or other Analogous Materials, of which the following is a full, clear, concise, and exact description, reference being had to the 10 accompanying drawing, forming a part of this specification.

This invention relates to girder bridges and to arch bridges which are made of concrete or other suitable material and to methods 15 of erecting the same, and has for its general object to provide an improved structure of the class referred to which shall combine a maximum of strength and efficiency with increased economy of construction, compared 20 with similar bridges at present in use.

The improvements to which my invention is directed pertain more directly to the spandrels, copings and railings of such bridges, and to methods of so erecting structures as 25 will produce an efficient and satisfactory superstructure.

My invention will be readily understood upon reference to the accompanying drawings illustrating the same in the preferred 30 forms and constructions of its several features, wherein:

Figure 1 is a side elevational view of substantially a longitudinal half of the bridge built in accordance with my invention. 35 Fig. 2 is a top plan view of the same. Fig. 3 is a cross-sectional view on the line 3—3 of Fig. 1. Figs. 4 and 5 are similar to Figs. 1 and 2, showing an arch. Fig. 6 is a cross-sectional view on the line 6—6 of Fig. 4. 40 Fig. 7 illustrates certain novel steps in the process of constructing the bridge. Fig. 8 is a cross-sectional view on the line 8—8 of Fig. 7.

Referring to Figs. 1, 2, and 3, which show 45 a bridge of the girder type, and first briefly specifying the structural elements of the bridge, 15 designates the girder, 16 the abutment, 17 the wings, 18 the spandrel, and 18^a the coping; 19 designates a concrete railing 50 mounted on the coping, 20 a pavement extending across the bed of the stream, 21 a protecting apron, 22 and 22^a embedded reinforcing members, and 24 a tie rod from wing to spandrel.

55 Figs. 4 and 5 show a bridge of the arch

type, in which 15 represents the arch, and the other reference numbers designate the same parts as indicated in Figs. 1, 2, and 3.

Fig. 6 is a section taken near the end of span of the arch bridge, showing the spandrels, railings and copings supported upon the arch, all represented by the same reference numbers as in Figs. 4 and 5.

Fig. 7 illustrates the process of construction; in this figure 25 designates the footing, 60 15 and 20 designate the arch or girder and the pavement as in former figures, 26 designates the centers, 27 the earth filling and 28 the railing forms. The pavement 20 rests upon the footing 25 which has a serrated upper surface inclined upwardly away from the end of the span.

For arch bridges of comparatively long span, hollow spandrel filling is frequently employed instead of the heavier earth filling. 75 One form of hollow span construction is shown at 29 in Fig. 7. The upright columns 30 support a solid roadbed 31. The spaces 32 between the columns may extend through the faces of the spandrels as shown at 33 in 80 Fig. 8, or may be screened by solid spandrel walls as shown at 34 in the same figure. The other reference numbers of Fig. 8 are applied similarly to Fig. 7.

When a bridge built of concrete or any 85 hardened plastic is subjected to the loading stresses of its own weight or of any applied load, such as spandrel filling or a concentrated load, a settlement of the structure results that has a tendency to crack the material of the arch or spandrel or railing at points of greatest tension. When the centers are struck in such a structure permitting the material to assume its principal stresses for possibly the first time, the settlement of 90 an arch or girder at the middle of the span is sometimes considerable and may result in a tension region along the outer surface near the ends of the span. When the spandrels are built in the usual way complete before 95 settlement of the arch or girder, a high degree of tension may result in the spandrel or railing above these points. To obviate the cracking that would otherwise result, vertical expansion joints have hitherto been introduced 100 in the spandrel at or near the ends of the span; such joints are nothing more than attempts to localize the cracks. Reinforcement of the spandrels through these regions 105 of tension has also been employed, but as the 110

2
stresses are largely indeterminate it has been impossible to adequately and efficiently resist them by such methods.

My invention consists of a bridge built in such a way that the arch or girder will have assumed its settlement, stresses while the spandrels and railings, or any part of them that is desirable, shall be substantially free from the stresses due to settlement of the arch or girder. To this end my invention comprehends a novel method of constructing such a bridge, the principal steps of which are as follows:—I first build a concrete footing at each end of the span indicated at 25 in Fig. 7. I next erect the centering and forms as shown in Fig. 7 and complete the arch or girder and spandrel to the lower side of the spandrel coping or at a line above the coping, or to any intermediate line. When the concrete pavement is employed, I lay this across the stream from footing to footing and then erect the false work or centering thereupon. Instead of completing the girder or arch and spandrel to a line above the coping of the spandrels I may complete the spandrel to a line slightly above the arch or girder or to any intermediate position. Or the centers may be erected first and the footings and arch or girder built next. The next step consists in striking or removing the centers and forms, that is in so manipulating the supports that the arch or girder will assume loading stresses, after which the spandrels, copings and railings or other superstructure may be added. The supports may be released by striking the wedges under the uprights, or by permitting the escape of sand from the sand boxes under the uprights, or by removing the sway bracing from flexible uprights, or any other method that will induce in the arch or girder some or all of the loading stresses which it is designed to resist. It is not, of course, essential to the success of this method that all of the centering should be removed or released from the arch or girder, but only that part of it be removed or released which shall cause the structure to assume desired stresses. It may be desirable, for example, to retain a portion of the centering in the structure after it has assumed some stress in order to stiffen the structure and support it until a part of the superstructure is added, or until the superstructure is completed, sufficient to stiffen the structure and prevent buckling of the arch or girder, after which the rest of the centering may be removed.

Before striking or removing the centers, the arch or girder may be loaded with the earth fill or any other loading and the centers then struck or removed and the railings, copings and spandrels or other superstructure continued or completed. The addition of the lower part of the spandrel walls before striking centers permits the addition of the

earth fill supported by these walls and thus applies to the arch its normal loading at the time the centers are struck. These part spandrels also serve to stiffen the arch and prevent distortion and possible collapse that might occur if the slender arch ring were subjected to stress without any of the superimposed loading for which it was designed. This is especially true where the part spandrel loading referred to consists of spandrel arches or other superstructure, and it is intended in such cases that the spandrels or superstructure shall be built in a substantially balanced arrangement to sustain the arch and prevent its buckling when subjected to stress.

After completing the arch or girder and while waiting for it to harden before striking or removing the centers the forms for the spandrel and railing, if to be of concrete, may be built so that after the centers are removed from the structure the only work required to complete it is the placing of the concrete in the forms. The work may be so divided that only the railing forms or the railing and coping forms will require filling with concrete after releasing the centers. In the meantime these railing forms will serve as temporary railings to protect traffic passing over the bridge while the arch or girder is hardening and the fill is settling. After the fill is completed, the workmen can build the railing with the advantage of requiring no scaffold since they then have the completed roadway on which to stand and place their materials. My process consists then primarily in subjecting the arch or girder to load stresses before adding the railings, copings, or upper part of spandrels, and to this may be added the feature of applying the load of earth filling or any other load to the bridge before subjecting it to stress. And in connection with this latter feature the forms for the upper part of spandrel, or coping or railing, or any part of them may be added before the structure is subjected to stress, and filled with concrete as the final step in the erection and loading, after which the centers may be completely removed if not previously accomplished.

In loading the bridge with earth filling before subjecting it to stress, the spandrel walls may be erected just sufficiently to hold the filling or other loading before the material of the structure is subjected to stress and subsequently extended or completed after the material of the structure is under stress. It will thus be seen that by first subjecting the arch or girder to a sufficient portion of load stresses to bring it into a more nearly normal condition of loading, the upper part of the spandrels and the copings and railings, or any part of them can be added without danger of later distortion due to settlement of the structure thus obviating the cracking

that otherwise would occur in the stiff railing and coping, and largely eliminating the danger of the arch ring breaking away from the spandrel along its face as so frequently occurs in arches as formerly constructed.

I claim:—

1. That improvement in the art of building an arch comprising first placing the footings with upper surface upwardly inclined away from the span, then laying a pavement between the footings, then erecting centers on the pavement, then erecting the arch of plastic material on the centers, then erecting part of the spandrel or superstructure approximately to the copings, then adding the earth filling, pavement, or other loading, then erecting the forms for railing, coping, or upper spandrel, then permitting the arch to harden, then releasing the centering supports, then allowing the arch to settle, then completing the spandrel, coping or railing, and subsequently removing the centering.

2. That improvement in the art of building an arch or girder comprising placing the foundations for the arch or girder, then laying a pavement between the foundations, then erecting temporary supports on the pavement, then erecting the arch or girder on the temporary supports, then erecting part of the spandrel or superstructure, then loading the structure, then erecting forms for railing or coping, then releasing the temporary supports, then allowing the arch or girder to settle, then adding to the spandrel or superstructure, and subsequently removing the centering.

3. That improvement in the art of building an arch or girder of hardening plastic comprising placing the foundations, then laying a pavement between the foundations, then erecting temporary supports on the pavement, then erecting the arch or girder on the temporary supports, then erecting part of the spandrel or superstructure, then adding part of the fixed loading, then erecting railing falsework, then releasing the temporary supports allowing the arch or girder to settle, then adding to spandrel, railing or superstructure, and subsequently removing the centering.

4. That improvement in the art of building an arch or girder comprising placing foundations for temporary supports, erecting temporary supports upon the foundations, then erecting an arch or girder on the temporary supports, then erecting the lower part of the spandrel or superstructure, then adding fixed loading, then erecting railing falsework, then releasing the temporary supports to allow settlement, then adding to spandrel, railing, or superstructure, and subsequently removing the temporary supports.

5. That improvement in the art of building an arch or girder of hardening plastic comprising laying foundations of plastic for

temporary supports, erecting temporary supports upon the foundations, then erecting an arch or girder on the supports, then erecting part of the spandrel or superstructure on the arch or girder, then adding other fixed loading, then erecting falsework for coping or railing, then lowering the temporary supports, then adding spandrel, coping or railing of plastic material and subsequently removing all falsework.

6. That improvement in the art of building an arch or girder comprising erecting centers, then erecting an arch or girder on the centers, then erecting part of the spandrel or superstructure, then adding other loading, then erecting falsework for coping or railing, then striking the centers, then adding to spandrel, coping or railing, and subsequently removing centers.

7. That improvement in the art of building an arch or girder of hardening plastic comprising erecting centers, then erecting an arch or girder on the centers, then erecting part of the spandrel or superstructure, then adding to the loading, then erecting forms for coping or railing, then lowering the centers, then adding to spandrel, coping or railing, and subsequently removing the centers and forms.

8. That improvement in the art of building an arch or girder comprising erecting the arch or girder on temporary supports, together with part of the spandrel or superstructure, then adding to the load on the arch or girder, then erecting falsework for railing or coping, then manipulating the temporary supports so as to subject the arch or girder to stress without permitting excessive distortion, then adding to spandrel, coping or railing.

9. That improvement in the art of building an arch or girder of hardening plastic comprising erecting the arch or girder on temporary supports, together with part of the spandrel or superstructure, then adding to the load on the arch or girder, then erecting forms for railing or coping, then manipulating the temporary supports so as to subject the arch or girder to stress without permitting excessive distortion, then adding plastic material for spandrel, coping, or railing.

10. That improvement in the art of building an arch or girder comprising erecting the arch or girder on temporary supports, together with part of the spandrel or superstructure, then adding roadway filling, then erecting railing falsework, then lowering the temporary supports, and subsequently completing spandrel, coping or railing.

11. That improvement in the art of building an arch or girder of hardening plastic comprising erecting the arch or girder on centers together with part of the spandrel or superstructure, then building up the road-

- way, then erecting forms for coping or railing, then striking the centers, and subsequently completing the spandrel, coping or railing with plastic material.
- 5 12. That improvement in the art of building an arch or girder comprising erecting the arch or girder on temporary supports, then erecting part of the spandrel or superstructure, then adding other loading, then lowering the temporary supports and subsequently adding coping or railing.
13. That improvement in the art of building an arch or girder of hardening plastic comprising erecting the arch or girder on temporary supports, then adding part of the spandrel or superstructure, then increasing the loading, then lowering the temporary supports and subsequently completing spandrel, coping or railing.
- 20 14. That improvement in the art of building an arch or girder comprising erecting the arch or girder together with part of the spandrel or superstructure on centers, then lowering the centers and subsequently adding coping or railing.
15. That improvement in the art of building an arch or girder of hardening plastic comprising erecting the arch or girder and part of the spandrel or superstructure approximately to the coping, on temporary supports, then lowering the supports, and subsequently adding coping and railing.
- 30 16. That improvement in the art of building an arch or girder of concrete comprising erecting the arch or girder together with part of the spandrel or superstructure, then manipulating the supports of the arch or girder to permit settlement, and subsequently completing the spandrel, coping or railing.
- 40 17. That improvement in the art of construction comprising erecting a supporting structure of concrete together with part of the supported superstructure integral therewith, then subjecting the supporting structure to its principal loading stresses and subsequently completing the superstructure.
18. That improvement in the art of building an arch or girder of concrete comprising erecting the arch or girder together with part of the integral superstructure supported thereby, and completing the superstructure after the arch or girder is subjected to its principal loading stresses.
- 55 19. That improvement in the art of construction comprising erecting a supporting structure of concrete together with part of the supported superstructure integral therewith, then subjecting the supporting structure to stresses induced by diminution of ex-
- internal support, and subsequently completing the superstructure.
20. That improvement in the art of building an arch or girder bridge of concrete comprising erecting the arch or girder together with part of the integral superstructure supported thereby, and completing the superstructure after the arch or girder is subjected to stresses induced by diminution of external support.
21. That improvement in the art of building an arch or girder bridge of concrete comprising erecting the arch or girder, then erecting part of the integral superstructure supported thereby, then applying additional loading, and subsequently adding to the superstructure after the arch or girder is subjected to its principal internal stresses.
22. That improvement in the art of building an arch or girder bridge of concrete comprising erecting the arch or girder together with part of its integral superstructure, then applying granular loading, and subsequently completing the superstructure after the arch or girder is subjected to stress.
23. That improvement in the art of building an arch or girder bridge of concrete comprising erecting the arch or girder together with part of its integral superstructure, then applying the other loading, then erecting forms for completion of superstructure, and subsequently placing the concrete for superstructure after the arch or girder is subjected to its principal stresses.
24. That improvement in the art of building a concrete bridge comprising erecting the bridge together with integral loading, and subsequently completing the integral loading after the bridge has assumed its principal stresses.
25. That improvement in the art of building a concrete bridge comprising laying a pavement, erecting centers upon the pavement, then erecting the bridge and spandrel approximately to the coping, then adding earth loading, then erecting forms for coping and railing, then manipulating the centers to cause the bridge to assume its principal stresses, then completing coping and railing and subsequently removing centers and forms.

In witness whereof, I have hereto subscribed my name in the presence of two witnesses.

DANIEL B. LUTEN.
